UNITED STATES PATENT OFFICE

ADOLPH F. WENDLER, OF BUFFALO, NEW YORK, ASSIGNOR TO THE NATIONAL ANILINE AND CHEMICAL CO., INC., OF NEW YORK, N. Y., A CORPORATION OF NEW YORK

DRIER AGITATOR

Application filed October 19, 1925. Serial No. 63,284.

This invention relates to agitators and in particular to agitators for horizontal driers for drying wet or moist material by evaporation of liquid therefrom.

Agitators, as commonly constructed for use with driers, are of two types, one, a continuous helix, commonly designated as spiral, and the other, a horizontal paddle. With each form it is found that the material becomes packed in spots and at times the consequent resistance becomes great enough to stall the machine or cause breakage, requiring stoppage of the drying operation. Furthermore, while the horizontal paddles provide a mixing and tumbling of the material, a long period for unloading is necessary. On the other hand, while the helical type accelerates unloading, the mixing and tumbling action is virtually absent, and the extended agitator periphery adjacent the drier shell and the allowance required for expansion does not permit adjustment to give a close contact with the drier shell and effect an efficient drying action.

By the present invention substantially even distribution of the material is maintained; and there is combined the mixing and tumbling operation of the paddle type with the endwise thrust and axial movement of the material which the helical type affords. Adjustability is at the same time provided so that efficient drying action is obtained.

A suitable apparatus embodying the invention comprises a plurality of material-contact members such as blades or paddles mounted in staggered relation about a shaft and in part or wholly helically formed to give axial or endwise movement to the material. For each paddle pitched in one direction, there is preferably provided another paddle pitched in the opposite direction so that the endwise shift of material in one axial direction is balanced by an endwise shift in the contrary axial direction. The paddles individually are in short sections, preferably being short

sections of a helix. The pitch of the blades is such that, in rotating, the forward portion of a blade is advanced a relatively small distance ahead of the rear portion; i. e. a projection of a blade upon a plane perpendicular to the axis of rotation subtends a relatively small arc, and consequently the blades can be given an adjustable mounting to bring them into as close a contact with the shell as inequalities therein will permit. Changes due to expansion can also be compensated by the adjustment so provided.

The relatively short paddles in staggered position about the shaft give an interrupted helical formation, so that there is no extended endwise travel of the material, and that which is so shifted by one blade is deposited in the path of an adjacent one. Accordingly the causes for packing or clogging are absent.

The forward face of the blades or paddles which contacts or bears against the material may extend normally to the shaft surface, but under such conditions there is a tendency for the material to ball up or roll into a pill formation. This action is corrected by providing the blades with a forwardly extending portion which is inclined rearwardly with respect to the direction of rotation. This inclined portion of the blades shears the material away from the casing and radially inward toward the shaft.

The shearing action not only maintains the material in a friable condition, but drying is hastened, particularly when a heated hollow shaft is used. Moreover, resistance to the agitator rotation, which arises in connection with normally set paddles due to the material being forced against the shell, is largely obviated; and the fact that the material is sheared rather than pushed considerably lessens the power consumption and wear on the parts, allows overloading without danger of breakage, and lessens dusting.

In the accompanying drawings, Fig. 1 is a longitudinal section of a drier

showing an agitator with the blades or paddles partially pitched along helical lines;

Fig. 2 is a cross-section of Fig. 1 on the line II-II;

5 Figs. 3 and 4 are details showing the bracket construction;

Fig. 5 is a partial section of the hollow shaft;

Fig. 6 is a side view of the dipper shown 10 in Fig. 5;

Figs. 7 and 8 are views of the paddle shown in Fig. 1;

15 Fig. 9 is a longitudinal section similar to Fig. 1 but disclosing sets of paddles alternating in pitch;

Fig. 10 is a partial cross-section of Fig. 9;

Fig. 11 is an elevation of the paddle shown in Fig. 10; and

20 Fig. 12 is a cross-section of another embodiment showing a modified form of arm and paddle, the paddles of each set alternating in pitch.

The embodiment, illustrated in Figs. 1 and 2, is one in which the blades are in part 25 pitched about the shaft surface. A cylindrical shell or casing 1 has a drying chamber surrounded by a jacket 2 so that steam or other heating medium may be circulated within it. Heads 3 and 4 close each end of 30 the casing and bearings 5 and 6 are carried by the heads. Within the bearings rotate trunnions 7 and 8, and connecting the trunnions is an extra heavy pipe shaft 9 which has a shrink tight fit in the trunnions and is 35 further secured to them by patch bolts 10 and welding. Each trunnion has an axial passage 11 through it for the entrance and exit of a heating medium; and, when steam or other condensable medium is used, the outlet 40 passage is preferably provided with a pipe 12 threaded in it, which pipe carries a dipper 13. The dipper has a lower surface 14 contiguous to the interior surface of the pipe shaft, and water of condensation is picked 45 up and so removed from the hollow shaft by the dipper as it rotates with the shaft.

Vapors given off during the drying are withdrawn in any well known manner, and the dried material is removed by opening the 50 normally closed discharge ports 50.

Encircling the revoluble shaft are a plurality of brackets 15, each one having arms 16 extending radially and four arms being shown to each bracket. The brackets are in 55 half sections bolted together and are held from rotation on the shaft by keys 17. In each arm is a slot 18. Connecting an arm of one bracket to an arm of an adjacent bracket is a paddle 20, which has lugs 21 extending from it at each end. Bolts 22 secure the lugs to the arms, the bolts passing through the slots 18 in the arms, and a pair of bolts are provided for each lug to hold it securely 60 and overcome any tendency to vibration. 65 The slot permits radial adjustment of the

blade. Two paddles or blades, lying diametrically opposite and pitched to move material in the same axial direction, are shown connecting each pair of brackets and constitute a set. There are therefore two sets of 70 blades connected to each bracket, with the exception of the end brackets, one set being offset and axially displaced from the other. Obviously a set may comprise more than two blades, and the offset be any desired angle. 75

The paddle construction, illustrated in connection with this embodiment, is one of cast steel having a forwardly extending, rearwardly inclined portion 23 and a cutting edge 24 to shear through the material. To give stiffness, the middle section 25 of the 80 blade is made wider, and a rib 26 at the rear of the blade further strengthens it.

Some of the paddles are helically bent and others are parallel to the shaft axis. As 85 shown in Fig. 1, on each side of a parallel mounted paddle is secured a helically bent paddle pitched to throw material toward it. The parallel paddle in view of its enlarged 90 middle section has a tendency to return material toward the helical paddles; and as the material is sheared through and lifted by the parallel paddles, an axial movement of the material as a whole is neutralized by the reverse pitch of the helical paddles. The staggered arrangement gives a freedom of flow so 95 that there is no packing or clogging.

The angle subtended by a projection of a 100 pitched blade upon a plane perpendicular to the shaft axis is preferably within a range from 15° to 45° to permit its ready adjustment to the shell surface and to give allowance for expansion. Each paddle, therefore, is in effect a short section of a helix. 105 Accordingly the staggered relation places axially adjacent paddles within wholly different segments or quarter cross sections.

Other embodiments in which the axially adjacent paddles or blades are alternately pitched, individually or in multiple, are 110 shown in Figs. 9 to 12 inclusive. The casing, shaft and bracket construction of Figs. 9 to 11, inclusive, is the same as in the preceding form, the difference lying in the paddles and their mounting. The paddle here illustrated 115 consists of a sheet metal blade portion 30 and extending lugs 31, 32; the end portions 33, 34 of the blade, carrying the lugs, are in a bent position so as to be parallel to the shaft axis, and the whole blade length is in a forwardly 120 extended position, the blade inclining rearwardly with respect to the direction of rotation, preferably at an angle of about 30° from the normal. A cutting edge 35 is given the outer or forward edge by beveling it as shown, and the beveling is made to conform to the shell so as to bring the cutting edge in close 125 proximity to the shell.

In the forms of the device shown in Figs. 9 to 12, the interposed parallel paddle is miss- 130

ing. Consequently material contracted by one helical-blade is sheared axially or endwise into the path of an adjoining blade. The adjoining blade pitched in the opposite direction as shown in Figure 9 returns the material to be acted upon by the first one. The result is an effective tumbling and mixing of the material which hastens the drying and lessens dusting. If instead of the axially adjacent blades being pitched in the opposite directions, a multiple of axially adjoining blades pitched in the same direction are followed by a multiple of axially adjoining blades pitched in the opposite direction, as shown in Fig. 12, the material is pushed a greater axial distance before its axial direction is reversed.

The paddles illustrated in Figs. 9 to 11 are of plate steel, as this material is satisfactory, relatively inexpensive, and the blades can be readily constructed; the helical form gives the requisite stiffness to withstand distortion. For simplicity, ease of installation, and need for but one type, brackets with normally extending arms and faces parallel to the axial plane are preferred. But other forms of arms and other types of paddle are feasible. As an illustration, Fig. 12 shows an arm 40 having an extension 41 which is bent from the normal to give the desired rake and is skewed from the axial plane at the desired pitch. For use with such an arm, a blade 42 is bolted to the extensions 41, and the extending lugs from the blade are omitted. A stiffening rib 43 is shown in the back of the blade and the blade is further shown as extending on either side beyond the bracket arms.

Whereas the pairs of blades of each set shown in Figures 1 and 9 are pitched to move material in the same axial direction, they may be oppositely pitched, as shown in Figure 12; and moreover, instead of those helical blades which lie in one segment of the axis being oppositely pitched with respect to each other as shown in Figure 1, they may be all pitched in the same direction, as shown in Figure 9. Obviously the blades lying in the same segment of the axis in the embodiment of Figure 9 may be also reversed with respect to each other, as are the helical blades shown in Figure 1.

The disclosed embodiments illustrate the mounting of the paddles on the shaft with adjacent sets of blades using a bracket in common, but different arms to stagger one set with relation to the next. Evidently independent brackets for each set can be used, the paddles may be overlapped and the staggered relation may be altered or partially omitted. Moreover, while the disclosure is directed to adjacent sets of paddles having a reverse pitch, it is obvious that paddles may be arranged in multiple having the same directional pitch with or without the stag-

gered conformation, and similar arrangement of multiple paddles pitched in the opposite direction, equal in number when no movement of the material body as a whole in one direction or the other is desired; with such an arrangement, it is desirable that multiple blades pitched in one direction be followed in rotation by multiple paddles pitched in the contrary direction. However, as the constructions disclosed give satisfactory drying and operating results, they are preferred in view of the simplicity and ease of erection.

Where in the claims a blade is referred to as "subtending an arc ranging from 15° to 45°", it is to be understood that a projection of the blade upon a plane perpendicular to the axis of rotation of the blade will subtend an arc of rotation ranging from 15° to 45°.

I claim:

1. In an apparatus for drying wet or moist material by evaporation of liquid therefrom, and having in combination a casing and an agitator cooperating therewith, the improvement which comprises an agitator shaft, and a plurality of sets of paddles mounted along said shaft and having a helical pitch, the length of the paddles constituting the sets being such as to extend through a segment not substantially more than 45°, alternate sets of paddles having reversed helical directions, and each of said paddles being adapted to cooperate with a wall of said casing.

2. In an apparatus for drying wet or moist material by evaporation of liquid therefrom, and having in combination a horizontal, stationary, cylindrical casing and an agitator adapted to cooperate therewith, the improvement which comprises a revoluble agitator shaft axially disposed within said casing, and a plurality of sets of paddles mounted along said shaft and having a helical pitch, alternate sets of paddles having reversed helical directions, and said paddles having a forwardly extending portion inclined from the normal to the shaft axis, and being disposed adjacent the inner wall of the casing whereby the paddles cooperate with said wall in shearing relation.

3. In an apparatus for drying wet or moist material by evaporation of liquid therefrom, and having in combination a horizontal, stationary casing and an agitator adapted to cooperate therewith, the improvement which comprises a horizontal, revoluble, agitator shaft axially disposed within said casing, arms extending radially from said shaft, alternate axially disposed arms lying in one axial plane and intermediate axially disposed arms lying in an axial plane in angular relation to the first named plane, the angle between said planes ranging from 15° to 45°, and material-contact members connecting adjacent arms, the length of said material-contact members being such as to extend through a segment of not substantially more than 45°,

- 5 said members being positioned to cooperate with a wall of said casing, and the axially adjacent ends of axially adjacent members being staggered circumferentially.

5 4. In an apparatus for drying wet or moist material by evaporation of liquid therefrom, and having in combination a cylindrical casing and an agitator adapted to cooperate therewith, the improvement which comprises

10 a revoluble agitator shaft axially disposed within said casing, a plurality of sets of helical blades of relatively short section connected to said shaft, alternate sets of blades having reversed helical directions, and said

15 blades subtending an arc ranging from 15° to 45° and being inclined rearwardly from a normal to the shaft surface.

5 5. In an apparatus for drying wet or moist material by evaporation of liquid therefrom, and having in combination a stationary, horizontal, cylindrical casing and a revoluble agitator adapted to cooperate therewith, the improvement which comprises a revoluble, horizontal, agitator shaft axially disposed

20 within said casing, arms extending from said shaft, and blades of helical conformation and of relatively short section adjustably secured to said arms by means of lugs, said blades being inclined rearwardly from a normal to

25 the shaft surface and beveled to give a forward cutting edge.

6 6. In an apparatus for drying wet or moist material by evaporation of liquid therefrom, and having in combination a heated casing and an agitator adapted to cooperate therewith, the improvement which comprises an agitator having means for moving material in a rotary direction while in contact with the inner wall of said casing, means for shearing said material from contact with said wall, and means for shifting said material back and forth in axial directions while in contact with said wall.

7 7. In an apparatus for drying wet or moist material by evaporation of liquid therefrom, and having in combination a heated casing and an agitator adapted to cooperate therewith, the improvement which comprises an agitator shaft, means carried by said shaft

30 for moving material in a rotary direction while in contact with the inner wall of said casing, means carried by said shaft for shifting said material in one axial direction while shearing it from contact with said wall, and means carried by said shaft for shifting said material in the opposite axial direction while shearing it from contact with said wall.

8 8. In an apparatus for drying wet or moist material by evaporation of liquid therefrom, and having in combination a horizontal cylindrical casing and an agitator adapted

35 to cooperate therewith, the improvement which comprises a horizontal, revoluble agitator shaft axially disposed within said casing, a plurality of sets of arms extending

40 radially from said shaft, each set being disposed in a separate plane perpendicular to the axis of the shaft, and a plurality of pairs of diametrically opposed blades mounted

45 on the ends of said arms adjacent the inner wall of said casing, each of said blades being short, helical, and rearwardly inclined, and subtending an arc ranging from 15° to 45°.

9 9. In an apparatus for drying wet or moist material by evaporation of liquid therefrom, and having in combination a horizontal cylindrical casing and an agitator adapted

50 to cooperate therewith, the improvement which comprises a horizontal, revoluble agitator shaft axially disposed within said casing, a plurality of sets of arms extending

55 radially from said shaft, each set being disposed in a separate plane perpendicular to the axis of the shaft, and a plurality of relatively short, helical blades supported at the ends of said arms adjacent the inner wall of said casing and connecting the successive arms of a set alternately with arms of the adjacent sets, said blades subtending an arc ranging from 15° to 45° and being inclined rearwardly from a normal to the shaft surface.

10 10. In an apparatus for drying wet or moist material by evaporation of liquid therefrom, and having in combination a horizontal cylindrical casing and an agitator adapted to cooperate therewith, the improvement which comprises a horizontal, revoluble agitator shaft axially disposed within said casing, a plurality of sets of arms extending

60 radially from said shaft, each set being disposed in a separate plane perpendicular to the axis of the shaft, and a plurality of short, helical, rearwardly inclined blades mounted

65 in pairs on said arms in shearing relation with the inner wall of said casing, said blades connecting the successive arms of a set alternately with the arms of the adjacent sets, and the blades of a pair being diametrically opposed to each other and pitched to move material in opposite directions.

11 11. In an apparatus for drying wet or moist material by evaporation of liquid therefrom, and having in combination a casing and a revolvable agitator shaft within

70 said casing and adapted to cooperate therewith, the improvement which comprises a plurality of pairs of paddles of relatively short, substantially equal length mounted diametrically opposite each other on said shaft, one of the paddles in a pair having a helical pitch in one direction, the other paddle in said pair having a helical pitch in the opposite direction, whereby said paddles shift the material in opposite direction, each of said paddles being equally distanced from said shaft and positioned to cooperate in shearing relation with the wall of said casing.

12 12. In an apparatus for drying wet or

- moist material by evaporation of liquid therefrom, and having in combination a casing and a revolvable agitator shaft within said casing and adapted to cooperate therewith, the improvement which comprises a plurality of pairs of paddles of relatively short, substantially equal length mounted diametrically opposite each other on said shaft, the length of the paddles constituting 5 the pairs being such as to extend through a segment of not substantially more than 45°, one of the paddles in a pair having a helical pitch in one direction, the other paddle in said pair having a helical pitch in the opposite direction whereby said paddles shift the material in opposite directions, each of said paddles being equally distanced from said shaft and positioned to cooperate in shearing relation with the wall of said casing. 10
13. In an apparatus for drying wet or moist material by evaporation of liquid therefrom, and having in combination a casing and a revolvable agitator shaft within said casing and adapted to cooperate therewith, the improvement which comprises a plurality of pairs of paddles of relatively short, substantially equal length mounted diametrically opposite each other on said shaft, the length of the paddles constituting 15 the pairs being such as to extend through a segment of not substantially more than 45°, one of the paddles in a pair having a helical pitch in one direction, the other paddle in said pair having a helical pitch in the opposite direction whereby said paddles shift the material in opposite directions, each of said paddles being equally distanced from said shaft and positioned to cooperate in shearing relation with the wall of said casing. 20
13. In an apparatus for drying wet or moist material by evaporation of liquid therefrom, and having in combination a casing and a revolvable agitator shaft within said casing and adapted to cooperate therewith, the improvement which comprises a plurality of pairs of paddles of relatively short, substantially equal length mounted diametrically opposite each other on said shaft, the length of the paddles constituting 25 the pairs being such as to extend through a segment of not substantially more than 45°, one of the paddles in a pair having a helical pitch in one direction, the other paddle in said pair having a helical pitch in the opposite direction, whereby said paddles shift the material in opposite directions, said paddles being mounted so that the working faces of the paddles are inclined rearwardly from the normal to the shaft axis, each of 30 said paddles being equally distanced from said shaft and positioned to cooperate in shearing relation with the wall of said casing. 35
14. In an apparatus for drying wet or moist material by evaporation of liquid therefrom, and having in combination a horizontal casing and an agitator adapted to cooperate therewith, the improvement which comprises a horizontal revolvable agitator shaft axially disposed within said casing, arms extending from said shaft and disposed in spaced planes perpendicular to the axis of the shaft, blades having a helical pitch mounted on said arms and being rearwardly inclined 40 from the normal to the shaft axis, and means for adjusting said blades toward and away from the inner wall of the casing so as to cooperate in shearing relation with the inner wall of said casing. 45
15. In an apparatus for drying wet or moist material by evaporation of liquid therefrom, and having in combination a casing and an agitator cooperating therewith, the improvement which comprises an agitator shaft, a plurality of arms projecting from 50 said shaft, a plurality of sets of relatively short paddles carried by said arms and having a helical pitch, the paddles of a set being pitched to move material in the same direction; each paddle being supported by a pair 55
- said shaft, a plurality of sets of relatively short paddles carried by said arms and having a helical pitch, each paddle being supported by a pair of axially adjacent arms, the length of the paddles constituting the sets 60 being substantially equal and such as to extend through a segment of not substantially more than 45°, at least two adjacent sets of paddles having reversed helical directions, said paddles being mounted so that the working faces thereof are inclined rearwardly from the normal to the shaft axis, and each of said paddles being equally spaced from the shaft and positioned to cooperate in shearing relation with the walls of said casing. 65
16. In an apparatus for drying wet or moist material by evaporation of liquid therefrom and having in combination a casing and an agitator cooperating therewith, the improvement which comprises an agitator shaft and a plurality of sets of paddles mounted along said shaft, at least two of the paddles of a set being disposed diametrically opposite to each other, being substantially of the same length, and being constructed 70 and arranged to shift said material to be dried in opposite directions upon rotation of said shaft, and each of said paddles being equally distanced from said shaft and positioned to cooperate in shearing relation with the wall of said casing. 75
17. In an apparatus for drying wet or moist material by evaporation of liquid therefrom, and having in combination a horizontal cylindrical casing and an agitator adapted to cooperate therewith, the improvement which comprises a horizontal revolvable agitator shaft axially disposed within said casing, a plurality of sets of arms extending radially from said shaft, each set being disposed in a separate plane perpendicular to the axis of the shaft, and a plurality of relatively short, helical blades supported at the ends of said arms adjacent the inner wall of said casing and connecting the successive arms of a set alternately with arms of the adjacent sets, said blades subtending an arc ranging from 15° to 45° and being inclined rearwardly from a normal to the shaft surface, and at least a pair of blades lying between and carried by adjacent sets of arms, the blades between adjacent sets of arms being pitched to move material in the same direction. 80
18. In an apparatus for drying wet or moist material by evaporation of liquid therefrom, and having in combination a casing and an agitator cooperating therewith, the improvement which comprises an agitator shaft, a plurality of arms projecting from said shaft, a plurality of sets of relatively short paddles carried by said arms and having a helical pitch, the paddles of a set being pitched to move material in the same direction; each paddle being supported by a pair 85
